Inventor
Attorney

UNITED STATES PATENT OFFICE.

EDWARD E. DUFFY, OF SAN ANTONIO, TEXAS.

ANTIFRICTION DRAWBAR SUPPORT.

Application filed December 10, 1925. Serial No. 74,533.

My present invention has to do with the coupling means of railway cars, and more particularly to anti-friction means for supporting the draw bars of couplers.

5 The object of my said invention is the provision of improved means whereby incident to longitudinal and lateral movement of a draw bar when a railway car is in use the friction due to movements of the draw bar 10 in either of the directions indicated will be reduced to a minimum and wear of the draw bar will be averted and the usefulness of the draw bar and the adjacent portions of the car structure will be prolonged.

15 Other objects and practical advantages of the invention will be fully understood from the following description and claims when the same are read in connection with the drawings, accompanying and forming part 20 of this specification, in which:—

Figure 1 is a view showing a draw bar in side elevation and showing my improvement in section as properly arranged relative to the draw bar, the said showing being of the 25 best practical embodiment of my invention of which I am cognizant.

Figure 2 is a top plan view of my improvement per se.

Figure 3 is a front elevation of the same.

30 Figure 4 is a top plan view of a modified exemplification of my improvement, designed more particularly for use on heavy cars.

Similar numerals of reference designate 35 corresponding parts in Figures 1 to 3, to which reference will first be made.

I show in Figure 1 a portion of a car 1, and I also show at 2 the draw bar of a coupler, the said draw bar being provided at its outer end with a head 3, and being 40 capable of longitudinal and lateral movement relative to the portion 1 in accordance with accepted practice.

In accordance with my invention a body 45 4 is appropriately connected to the car structure in a horizontal plane below the draw bar 2. The said body 4 is chambered in its upper side as designated by 5, and in communication with the said chamber 5 and disposed at the bottom thereof are spaced 50 pockets 6, the said pockets 6 depending from the bottom of the chamber 5 about the proportional distance illustrated.

Disposed in the pockets 6 and arranged 55 with their greatest length in the direction of the length of the car are anti-friction rollers

7, said rollers 7 being capable of movement in the pockets 6 crosswise of the car and lengthwise of the body 4. It will also be readily apparent that the said rolls or rollers 7 are of such a diameter that they project 60 above the bottom of the chamber 5, Figures 1 and 3.

Superposed on the rolls 7 is a major roll 8, said roll 8 being movable in the chamber 5 and on the rolls 7 and in the direction of 65 the length of the car structure and at right angles or proximate right angles to the length of the body 4. The roll 8 is free to move about its axis in all positions and is also capable of free movement in the direction of the length of the car structure, and consequently it will be manifest that the said roll 8 will avert friction and frictional wear incident to longitudinal movements of the draw bar 2, and that when the draw bar 2 is 70 thrust or moved laterally the friction will be reduced by the endwise movement of approximate endwise movement of the rolling on the minor rolls 7.

As clearly illustrated in Figure 4, my improvement may be duplicated for heavy equipment, the modified construction shown in said figure including a body 4* with two chambers 5* therein and each chamber characterized by a comparatively deep pocket 85 6*, and each chamber equipped with minor rolls 7 and a major roll 8 identical with the corresponding elements before described with reference to Figures 1 to 3.

It will be apparent from the foregoing 90 that notwithstanding the simplicity, the compactness and the strength of my improvement, the improvement is highly efficient in serving the purposes indicated; also, that the improvement is susceptible of being 95 readily installed, and by the thorough manner in which movements longitudinally and laterally of the draw bar are eased, the improvement in addition to lessening wear is calculated to improve the efficiency of the 100 draw bar in accommodating itself to the swaying of the car and the movements of the car relative to other cars as when a train is passing through a curve.

While I prefer to employ a body such as 105 described for carrying the rolls or rollers 7 and 8, I do not desire to be understood as confining myself to the use of said body inasmuch as it is within the purview of my invention to mount the rolls or rollers 7 and 110

8 in different manners in different types of cars.

It will be appreciated, however, that a body in a single unit such as shown and described increases the facility with which my improvement may be applied to a car in association with a draw bar, and I therefore prefer to employ a body such as 4 or 4¹/₂ as part of my invention.

10 I have specifically described the construction and relative arrangement of the parts embraced in the present and preferred embodiment of my invention in order to impart a full, clear and exact understanding of said embodiment. I do not desire, however, to be understood as confining myself to the disclosed construction and arrangement of elements, my invention being defined by my appended claims within the scope of which 15 structural changes and changes in arrangement may be made without departure from my invention.

Having described my invention, what I claim and desire to secure by Letters-Patent, 20 is:—

1. The combination of a car, a draw bar, and an anti-friction draw bar support; the said support comprising a body connected with the car and having a chamber in its 25 upper side confronting the underside of the draw bar and also having spaced pockets depending from the said chamber, anti-friction rolls disposed and movable in said 30 pockets and crosswise of the car, and a major roll disposed and bearing on the first-named 35 rolls and contacting with the underside of

the draw bar and movable in the direction of the length of the car.

2. The combination of a car, a draw bar, capable of longitudinal and lateral movement, and anti-friction means carried by the car and disposed under the draw bar for reducing friction incident to longitudinal and lateral movements of the draw bar; the said anti-friction means comprising rolls movable 40 in the direction of the width of the car, and a roll disposed on and movable lengthwise of the first-named rollers and contacting with the underside of the draw bar and movable about its axis in the direction of the 45 length of the car.

3. The combination of a car, a longitudinally and laterally movable draw bar, carrying means disposed under the draw bar and connected with the car and having a 50 chamber confronting the underside of the draw bar and also having pockets depending from said chamber, crosswise movable rolls in said pockets, and a longitudinally movable roll superposed on the first-named 55 rolls and serving as the direct support for the draw bar.

4. Car equipment comprising a body with a chamber in its upper side and pockets depending from said chamber, rolls disposed 60 and movable in said pockets, and a roll superposed on the first-named rolls and movable on and lengthwise thereof in the said chamber.

In testimony whereof I affix my signature. 70

EDWARD E. DUFFY.
